MACHINE FOR APPLYING ROOFING MATERIAL

Roy A. Smith, Norwood, and Lytle L. Williams,
Walpole, Mass., assignors to Bird & Son, Inc.,
East Walpole, Mass., a corporation of Massachusetts

Application January 30, 1939, Serial No. 253,560

4 Claims. (Cl. 91—30)

This invention relates to a portable roofing machine adapted for use in bonding sheet roofing material to a roof, particularly in the fabrication of so-called "built-up" roofing.

The prevailing commercial method of fabricating built-up roofs involves the application of hot asphalt, pitch, tar, or other cementing or bonding material, either hot or cold, by means of a mop, the bonding material being spread over the strip to be covered is as uniform a layer as possible, and then a strip of the roofing material, such as felt, is applied on the bonding agent. Commonly, the strips of sheet material overlap each other, and several layers of alternating bonding material and sheet material are often built up.

By application in this manner, several difficulties arise, both in the operation of spreading the bonding agent and in the resulting roof. All roofs have surface irregularities, and since the sheet material is customarily applied from a roll, the sheet material, as it is applied, tends to bridge over depressions in the surface between the high points which the roll contacts. So also, if the strips are being overlapped, the later applied strip tends to bridge from the roof to the top of the previously applied adjacent strip leaving a decided gap between itself and the roof in the area adjacent a longitudinal edge of the previously applied strip. Consequently, unless the previously applied bonding agent completely fills such depressions or gaps caused by the bridging, air spaces will be left between the sheet material and certain portions of the bonding agent. Such air spaces become sealed and especially so when further layers are subsequently applied, and even if rolling or brushing of the roofing is resorted to, the trapped air is not satisfactorily removed. It has been evident that the presence of trapped air between any two layers reduces materially the serviceability of the roof, as under these conditions the sheet materials are subjected to a blistering action which results in a more rapid failure of the material.

Despite the exercise of exceeding care in the mopping operation, in the attempt to secure a surface which will receive the sheet material satisfactorily, the presence of these air spaces is practically unavoidable. One practice designed to eliminate the air spaces involves the application of a surplus of the bonding agent to the roof, so that as the roll of sheet material is passed over the coating, the bonding agent will flow along in front of the roll. This practice, however, results in an uncontrolled flow of the bond-

ing agent, and, especially where the roof is of the sloping type, is not at all satisfactory.

Our invention, therefore, has for its object mechanism which operates to secure a more perfect bonding of the sheet material to the roof or other layers, through elimination of trapped air spaces, thus increasing the useful life of the roof.

To this end, our machine insures application of the bonding agent in such manner that depressions caused by irregularities in the surface, or gaps caused by overlapping, will be substantially completely filled with bonding material, by reason of the fact that the exposed surface of each strip of bonding material conforms substantially to the path of a straight edge moved in a direction normal to the straight edge against and progressively over a width of the surface to be covered by a layer of combined strips of bonding agent and sheet material. Such surface configuration of the applied strip of bonding material permits subsequent application thereto of the strip of sheet material, of a width approximately equal to the width of the coating, without trapping undesirable amounts of air, by applying or pressing the sheet material onto the coated strip beneath or from a roll moved against and progressively over the coated surface with its axis disposed normally to the direction of its movement, and with its direction of movement the same as that of a straight edge in generating a path conforming to the exposed surface of the particular strip of bonding material to which the sheet material is being applied. In this manner, as the sheet material is applied, the axis of the roll will generate a path of substantially the same configuration as the exposed surface of the applied bonding material, and every portion of the particular strip of sheet material will therefore tend to contact the coating, thus minimizing the possibility of the presence of the detrimental air spaces.

The machine of our invention will be described in connection with the accompanying drawing, in which:

Fig. 1 is a perspective view of the machine;

Fig. 2 is a bottom plan view of the feeding device; and

Fig. 3 is a cross-sectional view taken along the lines 3—3 of Fig. 2.

As shown in Fig. 1, we provide a hopper or tank adapted to receive adhesive or cementing material, as asphalt, pitch, tar, or other material commonly used as bonding agents for sheet roofing materials. The hopper or tank 10 is

fixedly mounted on a frame 12, which is supported by rotary elements including wheels 14, 14 and a roll 16.

The roll 16 is adapted to feed sheet roofing material, as 18, from a supply roll 20, which may be conveniently mounted on an arbor 22 received in suitable slots in the frame 12 at the rear of the machine, as shown in Fig. 1. An idler roll 24, flanged or plain, may also be provided, journaled in the frame 12, to facilitate accurate feeding of the sheet material 18 from the roll 20 to the feeding roll 16.

A handle 26 is provided on the frame 12, and as is obvious, the handle may be so arranged as to permit a pivoting thereof, so that the machine may be pushed as well as pulled. With the handle in the position shown in Fig. 1, it will be understood that, as the machine is pulled by the handle, the sheet material 18 will be fed around the feed roll 16 onto the surface on which the machine is placed.

In order to coat the surface with the bonding agent contained in the hopper or tank 10, just prior to the contacting of the sheet material 18 on the surface, we provide a feeding device, generally indicated at A in Fig. 1, and shown further in Figs. 2 and 3.

This feeding device includes a T-shaped throat 40 attached to the bottom of the hopper or tank 10, and having a series of internal vertical ports 42, 42, etc., of any desired number, shown as ten in the accompanying drawing, leading downwardly. Inset in the top of the throat are two valve plates 44, 44, each of which has valve openings 46, 46, etc., adapted to register with the respective ports on each side of the throat. The valve plates 44, 44 are moved laterally of the throat, independently of each other, in order to close the ports 42, 42. These valves are operated through the medium of two rods 48, 48, resting on the bottom of the hopper and supported in a vertical position by passing loosely through a suitable bracket (not shown) in the hopper or tank 10. The rods are adapted for a rotary movement, and each of them has fixedly mounted adjacent the bottom thereof a link 50, having at its opposite end a pin 52 which extends downwardly into cross slots in the plates 44. The links 50 and pins 52 are so arranged that rotary movement of each of the rods 48 is transmitted into reciprocal lateral movement of the plates 44 to open or close ports 42.

While this suitable arrangement for the valves has been described, it is obvious that other forms of valve may be used, the specific form or position thereof not constituting a part of this invention.

The feeding device A is boxlike in form, providing a chamber which receives the bonding material from the ports 42, so as to confine a head or reservoir thereof upon the surface to be coated. The feeding device as shown in the accompanying drawing is mounted for a sliding vertical movement outside and relative to the throat 40, which movement is limited downwardly by virtue of the support thereof, which includes inverted bolts 60, attached to frame 12 and passing loosely through brackets 62 affixed one upon each side wall of the feeding device. While, by this arrangement, gravity will insure that the feeding device A will contact the surface of the roof, a spring 64 may be provided on each bolt 60 to aid gravity in yieldingly urging the feeding device downwardly against the surface to be coated. Other arrangements for connect-

ing the feeding device, so that the feeding device may be free to move vertically with respect to the throat may be used, for instance, flexible or hinged tubing or ducts.

5 The feeding device A terminates in a leading bottom edge 66 and confining side edges 68, 68, all three of which are disposed in a horizontal plane so as to confine the bonding agent, especially from uncontrolled flow laterally. To prevent the leading edge 66 from catching on projections, as nailheads, we have provided a roller 70 mounted in advance of the leading edge 66 for rotation in brackets 72, 72, each extending from the side of the feeding device A.

15 The rear wall of the feeding device A terminates above the horizontal plane in which the edges 66, 68, 68 are disposed, and is provided with a spreading element 80 mounted on the rear wall for vertical movement independent thereof, through the provision of supporting bolts 81, 81, extending through vertical slots in the element 80 into the rear wall, and bolts, 82, 82, screw threaded into brackets, 83, 83, fixed to the element 80, the bolts 82, 82 passing loosely through brackets 84, 84, fixed on the rear wall of feeding device A. Element 80 may thus be adjusted vertically relative to the feeding device A by rotation of the bolts 82. As with the feeding device A, each element 80 may likewise be provided with spring means 85 between the brackets 83 and 84, to urge the element 80 yieldingly downwardly towards the limit of its adjustment, controlled by contact of the head of the bolts 82 against the brackets 84.

30 35 When a bonding agent which requires application at elevated temperature is used, the feeding device A may be provided, as on its front wall as shown in Fig. 1, with a heating device 90, which may take the form shown as a firebox 40 for briquettes. Such a device is adapted to heat the entire feeding device A by conduction, including the element 80.

In use of the machine, the spreading element 80 is adjusted in accordance with the particular viscosity of the bonding agent being used. We have found it perfectly possible to adjust the element 80 so close to the surface that the bonding agent will not flow therefrom, despite the fact that the valves are open, until the machine is 45 moved across the surface. This, of course, results in a rather thin coating. As will be understood, the roller 70 and leading edge 66 will determine the particular position of the feeding device A as the machine progresses across a strip 50 of surface to be coated, the whole device A rising or falling as determined by the two highest points over which the feeding device A is passing at a given moment. The bonding agent is spread beneath the spreading element 80, and the maintenance of a reservoir of the agent confined upon the surface in the box-like feeding device A, just 55 ahead of the element 80, insures that the bonding material will be deposited over a predetermined width, and the intervening or other depressions in the particular strip of surface over which the machine passes will be filled with the bonding agent, so that the applied bonding agent 60 will have a surface configuration which conforms substantially to the path of movement of the straight edge 66.

65 Since the axis of the roll 16 is disposed parallel to the straight edge 66, it will assume substantially the same vertical angle when it passes over a certain portion of the roof, that the straight edge 66 assumed when it was over the same por-

tion of the roof. As a result, the point of first contact of the sheet roofing material 18 and the bonding material will be a straight line, the momentary angle of which to the surface will be determined by the same irregularities of the surface which determined the angle which the spreading element 80 made with the surface at the time of spreading the bonding agent over that particular portion of the surface. Therefore, despite irregularities in the surface, which may cause a wavy exposed surface of bonding agent, the sheet material will be applied and pressed onto the coated surface as the roll 16 passes through substantially the same waves, and every portion of the sheet material 18 will tend to contact and become firmly bonded to all portions of the surface of the applied bonding agent.

Successive application of the bonding agent and sheet material in this manner will produce results obviously not possible were the sheet material 18 subsequently applied in a direction transverse to the direction in which the adhesive was applied. This latter type of application would be comparable to the present method of mopping, which secures approximately similar and equally undesirable results.

The independently operating valves 44, 44 permit a coating operation of a width equal to one-half of the maximum coating width, since, as shown in Fig. 2, a dividing crossplate 92 may be provided in feeding device A to prevent interflow from one side of the reservoir to the other.

While our invention has been described as having a separate arbor for the sheet material roll 20, it will be obvious that the roll of material 20 could, if desired, be mounted so as to take the position of roll 16, and act both as the feeding roll and as one of the rotary supporting means for the frame 12.

Likewise, by modification not outside of the scope of our invention, the supporting wheels 14, 14 could be mounted to the rear of the spreading element if their point of contact with the surface were outside the sides 68, 68 of the feeding device A, or to the rear of roll 16.

While our invention as it has been described utilizes roll 16 as one supporting rotary element additional wheels may be provided for this purpose, and roll 16 used merely as an embedding roll, its pressure on the surface being determined by its own weight or increased by springs.

We claim:

1. In a machine of the class described, a hopper for a liquid bonding agent, means to support said hopper for movement over a surface, a feeding device associated with said hopper and adapted to contact said surface, said device forming a chamber adapted to confine a head of bonding agent received from said hopper against

said surface and terminating in bottom edges, including a leading edge and side edges disposed in a horizontal plane and a rear edge spaced above said plane and forming a spreading element, means supporting said feeding device for vertical movement independently of said hopper and its supporting means, said spreading element being mounted on said feeding device for vertical movement relative thereto, and means to adjust said spreading element towards and away from said horizontal plane.

2. In a machine of the class described, a hopper for a liquid bonding agent, means to support said hopper for movement over a surface, a feeding device associated with said hopper and adapted to contact said surface, said device forming a chamber adapted to confine a head of bonding agent received from said hopper against said surface and terminating in bottom edges, including a leading edge and side edges disposed in a horizontal plane and a rear edge spaced above said plane and forming a spreading element, means supporting said feeding device for vertical movement independently of said hopper and its supporting means, and means for adjusting said spreading element towards and away from said horizontal plane.

3. In a machine of the class described, a hopper for a liquid bonding agent, means to support said hopper for movement over a surface, a feeding device associated with said hopper and adapted to contact said surface, said device forming a chamber adapted to confine a head of bonding agent received from said hopper against said surface and terminating in bottom edges, including a leading edge and side edges disposed in a horizontal plane and a rear edge spaced above said plane and forming a spreading element, and means supporting said feeding device for vertical movement independently of said hopper and its supporting means.

4. In a machine of the class described, a hopper for a liquid bonding agent, means to support said hopper for movement over a surface, a feeding device associated with said hopper and adapted to contact said surface, said device forming a chamber adapted to confine a head of bonding agent received from said hopper against said surface and terminating in bottom edges, including a leading edge and side edges disposed in a horizontal plane and a rear edge spaced above said plane and forming a spreading element, means supporting said feeding device for vertical movement independently of said hopper and its supporting means, and heating means associated with said feeding device and adapted to heat said spreading element.
